US00D618618S

(12) **United States Design Patent**
Lee et al.

(10) **Patent No.:** US D618,618 S
(45) **Date of Patent:** ** Jun. 29, 2010

(54) **IN-CAR BATTERY CHARGER**

(75) Inventors: **Shawn Lee**, Shenzhen (CN); **Marcus Smith**, Cambridge (GB); **Jeremy David Osborne Ranger**, Farringdon (GB)

(73) Assignee: **Powertraveller Limited**

(**) Term: **14 Years**

(21) Appl. No.: **29/333,667**

(22) Filed: **Mar. 12, 2009**

(51) **LOC (9) Cl.** 13-03

(52) **U.S. Cl.** D13/144; D13/108; D13/110

(58) **Field of Classification Search** D13/102, D13/107-110, 118-119, 133, 144, 184; D14/155, D14/251, 253, 432, 434; 320/107-115; 439/300, 439/620, 638, 668-669, 675, 825; 363/146

See application file for complete search history.

(57) **CLAIM**

The ornamental design for a in-car battery charger, as shown and described.

DESCRIPTION

FIG. 1 is a right side view of a in-car battery charger showing our new design;

FIG. 2 is a left side view of the in-car battery charger;

FIG. 3 is a bottom view of the in-car battery charger;

FIG. 4 is a top view of the in-car battery charger;

FIG. 5 is a front view of the in-car battery charger

FIG. 6 is a back view of the in-car battery charger;

FIG. 7 is a perspective view of the in-car battery charger; and,

FIG. 8 is another perspective view of the in-car battery charger.

The broken lines shown in the drawings are included for the purpose of illustrating environmental structure and form no part of the claimed design.
